James St. Chappell, Chillicothe, Ohio

Letter's Patent.

The Schedule referred to in these Letters Patent and making part of the same containing a description in the words of the said, James St. Chappell himself, of his improvement in the art of drafting and cutting garments.

No allusion to these presents, shall come. To be it known that James St. Chappell of Chillicothe in the County of Ross and State of Ohio have invented a novel and useful improvement in the art of drafting and cutting garments and that the following is a full and exact description of the art, as invented and improved by me — The name of this improvement is the spherical system of drafting and cutting garments, and elastic square a measure Book accompanying the system. The drafts herewith sent are a representation of a Great Coat, & Vest, pantaloons, panty, Blakie, Frock, skirt collar, and lapells, and a Lady's Habit, all of which are formed by eight lines and points as the printed explanations fully show.

What in the aforesaid system differs from other systems of said art is, that the latter is based upon the divisions of the breast, waist or height of a person who graduated numbers to suit the convenience of the practitioner, one adds to the division of the breast measure, measures taken from the top of the back, round the front of the shoulder to the same point started from, from the starting point of the former measure to the middle of the back and to the waist, a standard accompanying the work is used to get the height and bottom of arm hole, while the aforesaid spherical system has its base and principles from whole measures, taken from a point of the body at a right angle in front of and bottom of arm hole & cye, for further particular see explanation for measuring and drafting coats. The elastic square is of elastic metal or wood, about each arm from twelve to eighteen inches long, one half or two inches wide the thickness according to the elasticity of the substance made of, for the application of use the ~~in~~ ⁱⁿ direction for measuring, in printed planlans. — The measure Book is for the purpose of Recording every direction on each end of the coat, the name & No on one end, and the other end the measure and number of the same as that
